UNITED STATES PATENT OFFICE.

JOHN O. ALMEN, OF SEATTLE, WASHINGTON.

INTERNAL-COMBUSTION ENGINE.

1,411,556.

Specification of Letters Patent.

Patented Apr. 4, 1922.

Substitute for application Serial No. 163,561, filed April 21, 1917. This application filed February 19, 1921. Serial No. 446,515.

To all whom it may concern:

Be it known that I, JOHN O. ALMEN, a citizen of the United States, and a resident of the city of Seattle, county of King, State 5 of Washington, have invented certain new and useful Improvements in Internal-Combustion Engines, of which the following is a specification.

This invention relates to internal combustion engines and more especially to improvements in engines of the type illustrated and described in U. S. patent application, Serial Number 114,982 filed by me August 15, 1916.

15 In an engine of the referred to type wherein is employed a wabbler actuated by a plurality of pistons reciprocating in cylinders disposed parallel to the driving shaft, an important problem is to connect said wabbler to the various pistons so as to minimize lateral strains and friction.

Another problem is to neutralize or overcome the vibrating movements imparted to the engine by the momentum of the reciprocating pistons.

Another problem is the design of a valve to withstand the relatively high temperature and pressure obtained within the engine cylinders, rendering it difficult to pack 30 and lubricate, and effect a non-leakable seat or joint, due to the presence of solids in the exhaust gases.

The object of my improvements is to provide mechanism and valves which will operate satisfactorily with a consequent increase in the efficiency of the engine.

With these and other minor objects in view, the invention consists in certain features of novelty in the construction, combination and arrangement of parts herein-after described, shown in the drawings and particularly pointed out in the claims.

In said drawings—

Figure 1 is a longitudinal sectional view 45 of an explosive engine embodying the present invention.

Figure 2 is a sectional view taken through line 2—2 of Figure 1.

Figure 3 is a fragmentary view partly in 50 side elevation and partly in longitudinal section, of a piston and its connection with one of the wabbler arms.

Figure 4 is a sectional view taken through line 4—4 of Figure 3.

Figure 5 is a sectional view through line 55 5—5 of Figure 1.

Figure 6 is an end elevation taken from the right hand side of Figure 1.

The engine is of the type in which the pistons reciprocate in a line parallel to the 60 crank shaft and effect rotation of the shaft through the medium of a wabbler which is mounted on the shaft in such a manner that its axis lies in inclined relation to the axis of the shaft.

The engine preferably contains a multiple of cylinders arranged in a circle about the shaft and also preferably consists of two sets of such cylinders on either side of the wabblers, for, altho one set of cylinders only is necessary, it will be seen that double the power will be generated by the use of two sets of cylinders at no great addition of parts, since one double ended piston may be made to serve in two opposed cylinders, and 70 also the wabbler is common to both.

The wabbler is mounted on the crank shaft, preferably on ball bearings, because of their low friction. However, they must be of such construction as to withstand both 80 radial and thrust loads. Plain or roller bearings may also be used in this position.

In an engine of two sets of cylinders, double ended, the wabbler is preferably placed between the cylinders, and connection 85 made between the piston and wabbler at the center of the piston. Since the path traced by any point on the wabbler is a curve, it is necessary that the joint to the piston be capable of universal action, which 90 is preferably accomplished by providing spherical extremities on the wabbler and a corresponding socket piece to connect to the piston.

When the engine is in operation, a turning effect is produced on the crank shaft and, therefore, an equal and opposite turning movement is set up in the engine structure, which gives the wabbler a tendency to rotate with respect to the cylinders and, therefore, means to prevent such rotation become necessary. Such means may consist of a bevel gear mounted on the wabbler meshing with a bevel gear of equal number 100

of teeth mounted to the cylinders, or of an extension from the wabbler running between guides attached to the cylinders.

In this engine, however, a new principle is employed. It will be seen that the spherical extremity of the wabbler will rise and fall on the arc of a circle as it reciprocates, further analysis will show that it moves from side to side a distance equal to the length of the arc, if permitted to follow its natural course, the combined result of these motions is such that the center of the sphere and also any other point lying in the plane perpendicular to the wabbler axis and passing through the intersection of the crank shaft axis and the axis of the wabbler describes a true circle in a plane perpendicular to the crank shaft axis. If, therefore, the joint from the wabbler to the piston be made to permit this circular motion, and at the same time to confine it to its natural limits, it will serve as means to prevent rotation of the wabbler by applying side pressure on the pistons. In the guide method of holding the wabbler, if the guide be made in a straight line, that part of the wabbler which lies radially in line with the guide will not be permitted its natural side motion and, therefore, the side motion of other points on the wabbler will be increased, setting up unbalanced forces. In the gear method all motions are true, but it offers disadvantages of construction. The principle used in this engine offers a wide choice of construction. The joint itself may be varied to consist of universal joints at each piston, or rolling cone, as illustrated in my application, filed March 6, 1917, Serial No. 152494, or in the construction of my application filed for reissue September 17, 1917, Serial No. 191876. As the construction of this joint is not made the basis for claims in this application, it is, therefore, understood that various methods may be employed for accomplishing this result, it is also not necessary that the piston oppose the turning tendency of the wabbler since obviously other reciprocating or non-reciprocating means may be employed.

As illustrated, the engine is provided with a frame having member 10 interposed between two members 11, the latter being bored to furnish pairs of axially aligned power cylinders 12, which are arranged parallel to and concentrically about the engine shaft 13. The pistons 14 for each pair of cylinders are rigidly connected to or formed integral with each other. Provided within each pair of pistons are spaced annular shoulders 15 against which are seated annular plates 16 serving as thrust bearings for orbitally movable blocks 17, each having a socket 17¹ disposed to accommodate the globular extremity 18 of an arm 18¹ which extends radially from a hub 18².

Said arms and hub constitute a wabbler whose hub is mounted by means, preferably of ball bearings 19, upon a journal 20 provided on a sleeve 20¹ which is secured by a key 20² to the engine shaft 13. Said journal is, moreover, arranged to have its axis inclined with respect to the shaft axis, so that the wabbler will be caused by the reciprocating movements of the various pistons to impart rotary movements to the shaft. The shaft at each end of the sleeve 20¹ is desirably journaled by means of ball bearings 21 provided in a housing 11¹ of the engine frame.

Provided in each end of a block 17 is a recess 22, which communicates with a recess 24 in the opposing face of the adjacent plate 16. 23 represents balls, one for each end of the block, and by extending into the respective communicating recesses 22, 24, serve to couple a block to the associated plates.

For the purpose of introducing a block, the recesses of the plates connect with apertures 24¹, into which the balls may be brought to temporarily withdraw them outside of the planes of the block ends. Said plates are secured against rotary motion relative to the cylinders, preferably by pins 25 engaging in holes provided in the peripheral walls of the latter, and through slots 27 provided in the plates.

In the arcuate movements of the wabbler extremities 18, the latter will each be caused to take a path in a plane rectangular to the axis of the associated piston, whose locus will describe a course resembling that of the numeral eight (8). To accommodate such movement, the respective recesses are made of somewhat greater diameters than that of the balls, and the communicating ones disposed to have their axes out of alinement with each other, as indicated in Figures 3 and 4.

The recesses at one end of a block are desirably disposed to be in offset relation to the axis of a piston and upon the diametrically opposite side the piston axis from the recesses at the other end of the block. This will be understood from an inspection of Figure 4, wherein, for clearness, the most adjacent recesses are respectively designated by 22 and 24, while those at the remote end of the block are denoted by 22¹ and 24¹ with the respective balls denoted by 23 and 23¹. The purpose of thus positioning the recesses is to render the balls capable of orbital travel and yet prevent any rotary motion occurring to the pistons.

As the outer end of each cylinder is a single port 12¹, serving for both gas inlet and outlet purposes. To regulate the flow of gases in both directions, I provide at each end of the engine a valve, see Figures 1 and 5, in the nature of a wheel having a substantially annular shaped rim portion 28, here-

inafter designated as the valve, connected by spokes 28¹ with a hub 28², which is rotatably mounted on an eccentric 29 which, as shown, is secured to the shaft 13 by means 5 of a key 30. The eccentrics 29, one for the valve at each end of the engine, are disposed to have their axes disposed at that side of the shaft axis so that the centrifugal force of the respective valves will be applied to 10 act counter to the unbalanced moments due to the reciprocation of the various pistons with respect to the shaft axis.

It is obvious that inertia forces of the wabbler and corresponding reciprocating 15 parts act in such manner as to cause excessive vibration unless counterbalanced. As illustrated in Figure 1, it is to be observed that all of the reciprocating weight above the crank shaft exerts a pressure to the right 20 since all points in this plane are being accelerated toward the left or are being retarded while moving to the right, and since all weight at these points oppose a change of state, a resulting inertia pressure is exerted 25 toward the right. For like reasons, all reciprocating weight below the shaft exerts a pressure toward the left. The result of the combined forces is to tend to cause rotation of the entire structure about an axis lying 30 in the plane of the wabbler perpendicular to the crank shaft. If the reciprocating weight be symmetrically disposed on the wabbler about its axis, then this unbalanced turning moment will be constant in intensity 35 for any position of the crank shaft and may, therefore, be opposed by counter-weights attached to the crank shaft, so placed and proportioned as to centrifugally set up a turning moment on the same axis, equal in intensity and opposite in direction to the inertia 40 moment. One such counter-weight should be placed to the right of the wabbler, as is shown, having its center of gravity above the crank shaft axis, and one should be placed to the left of the wabbler having 45 its center of gravity below the crank shaft axis. It will be seen that the eccentrics which carry the valves fulfill the conditions required of the counter-weights as to the position of their center of gravity. However, 50 the centrifugal force of the eccentrics themselves is not great enough to overcome the unbalanced inertia forces, but since the center of gravity of each valve lies on its axis of rotation, which is also the center line of the eccentric, the weight of the valve is added to the weight of the eccentric and then the combined centrifugal force is used to counterbalance the inertia forces as described. 55 The fact that the valves rotate upon their eccentrics does not effect their value as counterweights since such rotation does not change the position of their centers of gravity with respect to that of the eccentric.

The hub 28² is provided with peripherally disposed spur teeth 28³ which are successively engaged by the teeth 31 of an internal stationary gear which may desirably be formed about a relatively large circular 70 opening provided in a frame member 32 and concentric to the shaft axis.

It will be seen that rotation of the crank shaft will cause successive teeth of the valve gear to come into mesh with the internal 75 gear, which is attached to the cylinders, and since the valve gear contains a lesser number of teeth than the internal gear, a rotary motion will be imparted to the valve, while at the same time it is caused to reciprocate by 80 reason of its eccentric mounting.

By such devices the valve is caused to be rotated through the medium of the gear while being revolubly carried about the axis of the shaft with a resultant succession of 85 epicyclic movements being imparted to the valve. A valve is operable in a recess or chamber 33 provided in the engine end and seats against a wearing plate 34 at its inner end and at its opposite side against the adjacent head 35. Said head, as indicated by full and broken lines, respectively, in Figures 1 and 6, is provided with a circular intake manifold passage 36 having an opening 36¹ by which it may be connected with a 95 supply pipe, and a circular exhaust gas manifold 37, having an outlet at 37¹ whereby it may be connected to a discharge pipe. 90

Said passages are provided with ports, 36² and 37², one of each for the respective cylinders. The valve is, however, in an engine having the number of cylinders shown in the illustrated embodiment, provided with three passages, 38, for the intake gases, and three passages, 39, for the exhaust gases, said passages being located and inclined with respect to the axis of the engine so as to register, upon occasion, with the cylinder ports 25 and the appropriate ports of the manifold passages, and subject to the erratic 100 travel of the valve. The valve passages are for the purpose of making quick openings and closings of communication between the manifold ports and the cylinder ports, desirably made of substantially arcuate forms 105 in the plane of their travel, and are severally arranged, as shown in Figure 5, about axes of the cycloidal paths which they traverse in their revoluble travel. 110

The speed of rotation, direction of rotation and number of opening in the valve, 120 follow certain definite laws.

In this engine, containing seven cylinders, three sets of ports are employed, and the valve rotated one sixth of the crank shaft 125 speed on the opposite direction. However, it is possible to rotate the valve at one eighth the crank shaft speed providing it is rotated in the same direction as the crank shaft and containing four sets of ports. 130

Other changes in speed, direction and number of parts are obvious. It will be seen that definite division on the valves correspond in time and position to the piston strokes—
 5 that is, the part of the valve containing the intake passage will always be passing a cylinder port as the piston in that cylinder is moving on its out stroke, the part containing the exhaust passage moves by a cylinder
 10 during the in stroke and another section of the valve will always be opposite a cylinder port, while the piston is on compression stroke, and likewise, another section is moving opposite a cylinder port during expansion stroke. For these reasons three points
 15 on the valve midway between an exhaust and intake passage measured on the long arc always present themselves at a cylinder port at the time when the piston in that cylinder
 20 has completed the compression stroke and is ready to fire. If, therefore, spark plugs be placed in the valve at these points and caused to spark at the proper time, then only three plugs will be needed to serve seven cylinders
 25 and since they move with the valve they are exposed to only a relatively small amount of heat for they are present in the heat of combustion for only a short period of time and then move off to comparatively cool position, thus avoiding a common source of trouble.

40 represent ignition plugs carried by the valve and extending into pockets 41, which successively open into the cylinder ports 12¹.
 35 One of the terminals of each ignition plug may be grounded through the engine frame and the other terminal is provided with a brush, indicated by 42 in Figure 1, which wipes against a commutator formed of an
 40 electric conducting ring 43 secured to the respective head within a chamber 44 of the head.

44 represents insulating material interposed between the conducting rings and the
 45 engine structure, said rings having brush contacts 43¹ projecting through said insulating material for the respective pistons.

In operation, the balls 23 positioned within the communicating recesses 22 and 24, whose axes are in offset relations with each other and with respect to the axes of the associated pistons, serve to guide the blocks and extremities 18 of the wabbler arms 18¹ to partake of circular paths about axes 55 parallel to the shaft axis, thereby affording a helical travel to each block during a piston stroke.

A valve 28 has, through the office of the eccentric 29 and the gear drive, imparted thereto a succession of helical movements so as to not only effect quick port opening and closing movements, but likewise causes any point upon the valve to take such erratic paths that hard substances between the valve
 60 and its opposing surfaces will not cut or

abrade grooves therein, but will have a tendency to maintain the seats in perfectly plane surface.

At each of the ports 12¹ and interposed between the respective cylinder and a wearing plate 34, is an expandable ring 34¹ having its periphery taper in opposite directions from a central ridge to engage in conical shaped recesses in the plate and associated cylinders. Because of such sloping ends, the 75 rings in their tendency to expand, will exercise axial thrusts against the wearing plates to press the latter against the respective valves, which are thereby pressed against the ends of the engine. The rings 34¹ thus 80 not only provide close joints between a valve and both the engine head and a wearing plate, but also afford non-leakable communications between the valve ports and the passages in the wearing plate. A still further 85 function of the referred to rings is to secure the wearing plates from rotating.

It is well known that rotary valves of different types have been tried, and without exception have failed. Failure in the great 90 majority of cases being due to excessive heating or failure of lubrication, or both, since each would result in the other. Also, the tightness of the joint against leakage of the gases requires that good film of lubricant 95 be maintained between the rubbing surfaces. The problem of a rotary valve is, therefore, much simplified, if, at the start, it is known that lubricating conditions are good and with motion such as this valve has, in which 100 there are no two successive points on the valve which follow the same paths on the adjoining surface, the action is one that will greatly assist the spreading of the lubricant and also make improbable the destruction of 105 the surfaces through the action of foreign substances.

In order that the valve may be properly cooled, the adjoining surfaces are water cooled and since the film of lubricant is complete the conditions for the conduction of heat from the valve to the cooling medium are good.

What I claim as new is:

1. An engine of the class described having in combination a plurality of cylinders provided respectively with a single port, reciprocatory pistons within the respective cylinders, a shaft, operative connections between the pistons and shaft for driving the latter, a rotary valve eccentrically mounted upon said shaft and of such counterbalance as to set up a turning moment on the same axis equal in intensity and opposite in direction to the moment of the inertia forces 125 incident to the reciprocating weights about the shaft.

2. An engine of the class described having, in combination, a plurality of concentrically arranged cylinders, a single port for 130

each said cylinders, reciprocatory pistons within the respective cylinders, a shaft, operative connections between the pistons and shaft for driving the latter, a rotary valve 5 for controlling said ports for the admission and exhaust of gases to and from the cylinders, and means influenced by the rotation of said shaft whereby the inertia forces incident to the reciprocatory pistons will be 10 neutralized.

3. An engine of the class described having, in combination, a plurality of concentrically arranged cylinders, gas inlet and outlet ports therefor, a reciprocatory piston 15 in each of the cylinders, a shaft, concentric connections between the pistons and the shaft for driving the latter, a valve for said ports, said valve being actuated by the shaft, and eccentric means carried by said shaft 20 for neutralizing the inertia forces incident to the reciprocation of said pistons.

4. An engine of the class described having, in combination, a plurality of cylinders, a shaft arranged concentrically thereof, pistons arranged for reciprocatory movements 25 in the respective cylinders, operative connections between the pistons and the shaft for driving the latter and counterweights positioned upon said shaft and proportioned 30 as to centrifugally set up a turning moment on the same axis equal in intensity and opposite in direction to the moment of the inertia forces incident to the reciprocation of the pistons.

35 5. An engine of the class described having, in combination, a plurality of cylinders, a shaft arranged concentrically thereof and in parallel relations to the cylinder axis, pistons arranged for reciprocatory movements 40 in the respective cylinders, rotary valves for controlling the ports for admission and exhaust of gases to and from the cylinders, eccentrics mounted on said shaft adapted to carry said valves, one of said eccentrics disposed with its center of gravity above the 45 shafts axis and the other of said eccentrics disposed with its center of gravity below the shafts axis, whereby the centrifugal force exerted thereby will neutralize the inertia 50 forces incident to the reciprocation of the weights about said shaft.

6. An engine of the class described having a rotating valve for controlling the ports for the admission and exhaust of 55 gases to and from the cylinders thereof, and means for mounting said valve upon the shaft of said engine whereby, during its rotation no two successive points on the valve will follow the same path on the adjoining surface thereby rendering improbable the destruction of the abutting surfaces 60 through the action of foreign substances.

7. An engine of the class described having, in combination, a plurality of cylinders arranged concentrically with respect to

a shaft, driving connections between the pistons and the shaft, a valve for controlling the intake and exhaust passages of said cylinders, an eccentric rotatable with said shaft and serving as a journal bearing for the 70 valve, said valve being provided with gear teeth, and a non-rotatable gear engageable with said gear teeth and rendered operative by said eccentric to effect the rotation of the valve at a speed less than that of the 75 shaft.

8. An engine of the class described having, in combination, a plurality of cylinders arranged concentrically with respect to a shaft, driving connections between the pistons and the shaft, a valve for controlling the intake and exhaust passages of said cylinders, an eccentric rotatable with said shaft, and serving as a journal bearing for the 80 valve, said valve being provided with gear teeth, and a non-rotatable gear engageable with said gear teeth and rendered operative by said eccentric to coact with the latter and impart both rotary and radial movements 85 to the valve.

9. An engine of the class described having, in combination, a plurality of cylinders arranged concentrically with respect to a shaft, driving connections between the pistons and the shaft, a valve for controlling 95 the intake and exhaust passages of said cylinders, an eccentric rotatable with said shaft and serving as a journal bearing for the valve, and positive means rendered operative by the rotation of said eccentric whereby the 100 valve is caused to rotate while being revolvably carried by the eccentric.

10. An engine of the class described comprising, in combination, a shaft, a plurality of cylinders arranged in parallel relations 105 with and concentric of said shaft, a valve rotatable about an axis eccentric of the shaft, and provided with inlet and exhaust ports for the respective cylinders, means to rotate said valve, an ignition plug carried 110 by the valve into firing relations with the respective cylinders, a brush carried by said ignition plug, and an electrically connected commutator disposed in operative relations with said brush whereby the explosive 115 charges within the various cylinders will be periodically exploded.

11. An engine of the class described having, in combination, a plurality of cylinders having induction and exhaust ports, inlet 120 and exhaust manifold passages in the engine head, and respectively provided with ports, a wearing plate having apertures in correspondence with the aforesaid cylinder ports, a rotary valve operable between said 125 plate and the engine head and having ports adapted to be revolvably carried to afford communication between the ports of the aforesaid passages and the cylinder ports through the medium of the respective plate 130

apertures, and means serving to yieldingly hold the valve in juxtaposition with said engine head and the plate and also serving to afford a non-leakable connection between the cylinder ports and the plate aperture.

12. In an engine, an eccentric, means to rotate said eccentric, a valve for controlling the engine cylinder ports, said eccentric

serving as a journal bearing for the valve, and means operatively engaging said valve to rotate the same about the axis of the eccentric while being orbitally carried by the latter.

Signed at Seattle, Wash., this 14th day of February, 1921.

JOHN O. ALMEN.
